(57) **CLAIM**

The ornamental design for a lottery ticket dispenser, as shown and described.

DESCRIPTION

FIG. 1 is a front perspective view of a lottery ticket dispenser according to our new design. The dot-dot-dash broken lines represent unclaimed features of the design. The evenly spaced broken lines represent the boundaries of the claim, forming no part thereof; and,

FIG. 2 is an enlarged front elevational view of FIG. 1 with the dot-dot-dash broken lines removed.
